[57] CLAIM

The ornamental design for a wireless telephone, as shown and described.

DESCRIPTION

FIG. 1 is a top, left perspective view of a wireless telephone showing my new design;

FIG. 2 is a top, left perspective view thereof wherein the antenna is in the extended position;

FIG. 3 is a bottom, rear perspective view thereof, wherein the keyboard portion is in the closed position;

FIG. 4 is an exploded bottom rear perspective view with the keyboard in the closed position and the cap portion exploded from the main body;

FIG. 5 is a top plan view thereof;

FIG. 6 is a left side elevational view thereof;

FIG. 7 is a front elevational view thereof;

FIG. 8 is a bottom plan view thereof;

FIG. 9 is a right side elevational view thereof;

FIG. 10 is a rear elevational view thereof;

FIG. 11 is a reference perspective view thereof, wherein the wireless telephone is in the using condition;

FIG. 12 is a reference perspective view thereof, wherein the wireless telephone is in the using condition with the antenna is in the extended position, the portions shown in broken lines in FIGS. 11 and 12 are for an illustrative purpose only and form no part of the claimed design;

FIG. 13 is a top, left perspective view of a second embodiment of a wireless telephone showing my new design;

FIG. 14 is a top, left perspective view of the embodiment of FIG. 13 wherein the antenna is in the extended position;

FIG. 15 is a bottom, rear perspective view the embodiment of FIG. 13, wherein the keyboard portion is in the closed position;

FIG. 16 is an exploded bottom rear perspective view of the embodiment of FIG. 13 with the keyboard in the closed position and the cap portion exploded from the main body;

FIG. 17 is a top plan view the embodiment of FIG. 13;

FIG. 18 is a left side elevational view the embodiment of FIG. 13;

FIG. 19 is a front elevational view the embodiment of FIG. 13;

FIG. 20 is a bottom plan view the embodiment of FIG. 13;

FIG. 21 is a right side elevation view the embodiment of FIG. 13;

FIG. 22 is a rear elevational view the embodiment of FIG. 13;

FIG. 23 is a reference perspective view the embodiment of FIG. 13, wherein the wireless telephone is in the using condition; and.

FIG. 24 is a reference perspective view the embodiment of FIG. 13, wherein the wireless telephone is in the using condition with the antenna is in the extended position, the portions shown in broken lines in FIGS. 23 and 24 are for illustrative purposes only and form no part of the claimed design.
